UNITED STATES PATENT OFFICE

ERNEST LORENZ, OF NEW YORK, N. Y., ASSIGNOR TO WALTER SENNHAUSER, TRADING AS MIDDLESEX LACE AND EMBROIDERY WORKS, OF SOUTH RIVER, NEW JERSEY

DESIGN FOR LACE MEDALLION

Application filed November 20, 1930. Serial No. 37,731. Term of patent 3½ years.

To all whom it may concern:

Be it known that I, ERNEST LORENZ, a citizen of the United States, and residing in the county of New York, city of New York, and State of New York, have invented a new, original, and ornamental Design for Lace Medallion, of which the following is a specification, reference being had to the accompanying drawing, forming a part thereof.

The drawing is a view of lace medallion showing my new design.

I claim:

The ornamental design for lace medallion as shown.

This specification signed this 13th day of November, 1930.

ERNEST LORENZ.
